OPERATION OF COAL DISTILLATION PLANTS

Filed June 8, 1929

Fig. 1.

UNITED STATES PATENT OFFICE

STUART PARMELEE MILLER, OF ENGLEWOOD, NEW JERSEY, ASSIGNOR TO THE BARRETT COMPANY, OF NEW YORK, N. Y., A CORPORATION OF NEW JERSEY

OPERATION OF COAL DISTILLATION PLANTS

Application filed June 8, 1929. Serial No. 369,497.

This invention relates to improvements in the operation of coal distillation plants. It includes improved apparatus and the method of operation. It relates more particularly to a new and improved method of preparing creosoting compositions. The creosoting compositions are valuable substitutes for the ordinary coal tar solutions, so-called.

According to the present invention, hot coke oven gases or gas retort gases are employed for the distillation of tar by bringing the tar into direct and intimate contact with the hot gases and the resulting gases and vapors are cooled by blending them with other coke oven gases or gas retort gases which have not been employed for distillation of tar but have been cooled to a temperature below that of the hot enriched gases. The cooling of the gases not employed for distillation may be carried out in any of the usual ways as, for example, by spraying with ammonia liquor, etc. The blending of the cooled gases with the hot enriched gases causes condensation of vapors carried by the enriched gases and the separation of the oil from the gases causes removal from the blended gases of entrained impurities which are normally present in coke oven or gas retort gases. The oil condensed together with the tar or pitch particles removed from the gases forms a tarry oil which may be directly employed as a substitute for the ordinary creosoting compositions of the type known as coal tar solution. In special cases it may be desirable to add tar to these tarry oils before use as creosoting compositions.

In making ordinary coal tar solution, tar collected from coke oven gases is distilled and the distillate is blended with a relatively small proportion of undistilled tar usually in the proportion of 80% of distillate to 20% of tar to make the coal tar solutions of commerce. The distillation of this large amount of tar is expensive and when distilled by the usual methods considerable decomposition of oil takes place during the distillation with resulting loss of valuable

oil and corresponding increase in pitch production.

The proportions in which coal tar is blended with coal tar distillates in making coal tar solutions is governed by commercial 55 specifications which are of such a character as to require the distillation of a large amount of tar and the blending of only a limited amount of undistilled tar with a large amount of distillate; for example, 60 coal tar solutions are commonly limited to not more than 2% of so-called free carbon. The specifications also usually limit the amount of low boiling distillate, for example, to not more than 5% distillate up to 65 210° C. and not over 25% up to 235° C., while limitations are also imposed as to the character of the residue remaining after the distillation to a specified maximum temperature. 70

In my co-pending application Serial No. 354,477, I disclose and claim a process of preparing creosoting compositions and other tarry oils by blending coke oven gases which have been used for the distillation of tar 75 and are consequently enriched in condensable constituents with coal distillation gases which have not been so employed, and subsequently cooling the combined gases to separate tarry oil therefrom. 80

According to the present invention, the tarry oil desired is obtained by the blending of cooler coal distillation gases with hotter coal distillation gases which have been enriched in condensable constituents by the 85 distillation of tar therein. The tarry oil obtained is condensed by the cooling effect of the unenriched gases on the hotter enriched gases. This cooling may, when desired, be supplemented by indirect or direct 90 cooling, as with water or ammonia liquor, but the application covers more particularly the formation of oils due to the blending of the cooler gases with the hotter gases which have a relatively high vapor content. 95

By regulating the temperature of the cooler gas used for blending with and for cooling the hotter gas and especially by regulating the relative volumes of cool gas and hot gas, and by regulating the temperature 100

and composition of the hotter enriched gas, the temperature of the blended gases and the composition of the oils condensing therefrom can be controlled.

- 5 The distillation of the tar by the hot gases may be carried out in any suitable means. The enrichment may advantageously be such as to saturate or nearly saturate the gases with oil vapors so that on 10 cooling a high yield of oils will be obtained. By enriching the gases in condensable constituents the amount of pitch particles suspended in the gases as figured on the vapor content of the gases, is lower than the 15 amount of pitch particles normally suspended in the gases as figured on the original vapor content of the gases. If the enriched gases were cooled separately, a tarry oil would be obtained which would 20 have a lower percentage of free carbon than the free carbon present in the tarry oil which would be obtained by cooling the gases before enrichment. Furthermore, according to 25 the most advantageous methods of distilling tar in the gases, the tar is sprayed or atomized into the gases so that intimate contact between the tar and gases is obtained and a large surface of the tar is exposed to the action of the hot gases and efficient 30 distillation results. The spray of tar in the gases scrubs entrained pitch particles from the gases so that the gases and vapors resulting from the distillation contain actually a smaller amount of entrained impurities 35 and therefore on cooling, a smaller amount of free carbon would be obtained than would be obtained on cooling gases which have not been subjected to such a scrubbing action. A greater or less amount 40 of the free carbon content of the gases may be removed in the scrubbing action. Where the distillation is produced by an intense spray of the tar in the gases, the gases may 45 be thoroughly de-tarred so that a substantially clean oil would be obtained if these gases and vapors were subjected to cooling.
- According to this invention, gases which have been enriched by distillation with or without substantial scrubbing of the gases 50 so that the gases contain a relatively small percentage of free carbon as based on their oil vapor content are blended with coal distillation gases which have been subjected to the usual cooling treatment in a gas collector main. The blending of these cooler gases 55 with the enriched gases yields a gas with a free carbon content intermediate between that of the two gases considered separately and the blending of the gases cools the resulting mixture below the dewpoint of oil vapors carried by the mixed gases and causes 60 substantial condensation of such vapors and separation of the oils from the gases together with removal of a certain amount 65 of the entrained pitch particles and other

free-carbon-containing material. The result is a tarry oil of relatively low free carbon content. This tarry oil may have a sufficiently low content of so-called free carbon to enable it to be directly employed without the addition of distillate oil for making creosoting compositions. If the content of tarry matter, as evidenced by the content of so-called free carbon, is lower than desired in the tarry oil recovered, additional tar may be blended therewith but in any event the distillation of a large amount of tar to produce a large amount of distillate oil is made unnecessary.

By blending predetermined and regulated volumes of cooler gas and hot enriched gas, the temperature of the resulting blended gases can be controlled and the composition of the condensate condensed therefrom likewise controlled. For example, tar may be 80 distilled by the hot gases from four ovens and the hot enriched gases from this distilling operation may have a temperature of 250° C. This hot gas, which may be substantially saturated with oil vapors, may 85 then be mixed with the gas from twenty other ovens which has been cooled in the collector main in the usual way to a temperature of about 80° C. The blended gases will, as a result of such blending of hot and cool gas, have a temperature of about 108° C. and from the blended gases a condensate of 90 tarry oil will be thrown down. By regulating the temperatures of the hot and cool gases and the relative volumes of the same 95 which are blended, the temperature of the blended gas can be controlled. The lower the temperature of the blended gases the greater will be the proportion of lighter oils recovered, and the higher the temperature the smaller will be the proportion of 100 such lighter oil.

By proper regulation of the distillation of the tar by the hot coal distillation gases, a regulated proportion of the entrained 110 pitch particles can be removed from the gases and the distillation can be so regulated that the gases are enriched in oils of a particular boiling range. The gases which are not employed for distillation may be 115 cooled to the extent required to give the desired cooling and condensing of oils when the two gases are blended. By proper regulation tarry oil of the boiling range and free carbon content desired for creosoting 120 composition can be separated from the combined gases by blending enriched and unenriched gases which have been properly treated. It will be understood by those skilled in the art that the gases, after blend- 125 ing and following separation of the condensed oil, will still contain, to a greater or less degree, condensable coal tar light oils. The amount and character of such oils will depend upon several factors, the more im- 130

portant of which are the degree of enrichment of the gases used for distillation, the type of tar distilled, the relative quantities of enriched and unenriched gases blended, and the temperature of each gas blended. By control of these various factors creosoting compositions may be recovered by my process, which will have desired characteristics as to free carbon content, boiling range, and specific gravity, and which will contain, as desired, greater or lower proportions of the lower boiling coal tar oils. The lower boiling oils remaining in the gases as vapors after removal of the creosoting compositions may be recovered on further cooling of the gases directly or indirectly and represent secondary products of commercial value recoverable by the process of my invention.

20 The invention will be described in the accompanying drawing more particularly as applied to a coke oven plant, but it is intended and it is to be understood that the invention is not limited thereto.

25 Fig. 1 is a plan view of a coke oven battery equipped for carrying out the invention;

Fig. 2 is a somewhat enlarged section of the still shown in Fig. 1; and

30 Fig. 3 is a detail showing the gas mixing chamber of Fig. 1.

The drawing shows a coke oven battery 35 provided with uptake pipes 36 and a collector main 37 of the usual type. The gases 35 from the collector main pass into the center-box 38 and thence through the cross-over main 39 to the gas-mixing chamber 40. Here the gases are blended with gases which have been employed for the distillation of tar 40 in the tar still 41.

This tar still 41 is connected with the ovens through uptake pipes 42. These uptake pipes may advantageously be located at the rear of the ovens and the ovens connected with the uptake pipes 42 are also connected through the uptake pipes 36 with the collector main 37. By the proper manipulation of valves in the uptake pipes 36 and 42, the gases from these ovens of the battery 50 may be diverted either to the collector main 37 or to the still 41. Within the still is a roll 43 which is rotated by the motor 44 at a speed of, for example, 900-1200 R. P. M. The roll is situated in the still so that it dips 55 to a slight extent into a body of tar maintained within the bottom of the still. The rotation of the roll sprays the gases passing through the still with tar and the spray may be so intense as to scrub the gases passing through the still sufficiently to de-tar these gases. The resulting clean gases enriched in vapors distilled from the tar pass up through the tower 45 into the main 46 which enters the gas-mixing chamber 40.

60 The still 41, the uptake pipes 42, the tower

45 and the main 46 are advantageously well insulated.

The tar to be distilled may advantageously be admitted to the tower 45 through the spray nozzle 47 situated between the two 70 baffling means 48 and 49. The tar is pre-heated and preferably partially distilled within the tower and the undistilled residue which collects at the bottom of the tower is conducted through the line 50 into the body of the still 41. This tar is distilled within the still and may be distilled to a pitch with a melting point of 300 or 350° F. or even 400° F. The pitch is advantageously withdrawn from the still 80 through a trap 51 which is provided with a levelling arm 52 through which the pitch is drawn off from the still. Where a high melting point pitch is produced the pitch may advantageously be drawn off into a trough 53 in which it is brought into contact with a stream of cold water from the line 54 which granulates the pitch. The graduated pitch is conducted to the pitch storage tank 55 in which it may be separated from any adhering water in any suitable manner and may be used for any suitable purpose.

85 The hot enriched gases contain a high percentage of vapors and may be substantially saturated with such vapors. These enriched gases enter the bottom of the mixing tower 40 and admix within the tower with the unenriched gases from the main 39. The tower may contain suitable baffling means, as for example the baffles 56 to provide thorough inter-mixture of the gases. Although some small amount of cooling may be provided by direct or indirect means, as by a cold water or cold ammonia liquor spray, which may advantageously be admitted to the top of the tower, such additional cooling of the gases beyond the cooling effect of the unenriched gases on the enriched gases is not contemplated by this invention. The blending of the cooler gases with the hotter enriched gases reduces the temperature of the combined gases below the dewpoint of higher boiling constituents present in the combined gases and on separation of these constituents together with entrained pitch or tar particles which enter the mixing chamber with the unenriched gases through the main 39, a tarry oil is produced which is withdrawn through the line 57 into the tarry oil storage tank 58.

110 From this gas-blending tower the combined gases pass to condensing means 59 and then through the exhauster 60 to means for the recovery of ammonia and light oils.

115 Where the distillation of tar by the hot gases in the still 41 is carried sufficiently far to produce a high melting point pitch, higher boiling constituents such as resinous or greasy constituents which are solid or semi-

solid at ordinary temperatures may advantageously be recovered in a separate condenser, such as the hot condenser 61, before being blended with the cooler gases passing through the cross over main 39. This hot condenser may be an indirect tubular condenser which may be air-cooled or in which steam or a hot gas is employed for cooling the gases and separating the higher boiling constituents from the enriched gases. The condensate may be withdrawn through a line, preferably steam jacketed to the tank 62. Where separate collection of the higher boiling constituents is not desired, the gases may be by-passed through the line 63 and brought direct into the mixing chamber 40.

A mixing chamber such as that shown at 40 need not be employed. Other means for mixing the cool gases with the hot enriched gases may be employed. Where the main through which the mixed gases pass on their way to the condenser is sufficiently long to provide the required mixing of the gases and condensation and separation of the oils, special mixing means is not necessary.

A by-pass 64 is shown through which the gases may be conducted to the condenser when the still is not in use, and the coke oven is being operated in the usual way.

30. The cooling of the gases employed for distillation by cool gases not so employed, is such as to reduce the temperature of the combined gases below the dewpoint of the heavier condensable constituents within the gases and the removal of such condensable constituents from the gases, effects removal of entrained tarry impurities so that a tarry oil is produced. The tarry oil may be directly usable without further treatment for 35 creosoting purposes. If it contains too large a proportion of low boiling point constituents these can readily be removed by partial and limited distillation. Tar, e. g., such as the tarry oils from the condensers of an ordinary coke oven plant, may be blended with the tarry oil thus produced, or a small amount of coal tar distillate may be blended with the tarry oil where the free carbon content of the oil as produced is too high to 40 allow the use of the tarry oil directly for creosoting purposes. Tar or distillate of low boiling range may advantageously be added to the tarry oil where it is desirable to 45 lower its boiling range, tar or distillate being employed as an increase or decrease in the free carbon content of the tarry oil is desirable.

Although the invention has been described 50 more particularly in connection with the operation of a coke oven plant, it is intended and is to be understood that it is not limited thereto, but is applicable to other types of coal distillation plants, e. g., gas retort 55 plants, and other types of stills in which tar

is distilled by direct contact with hot coal distillation gases, may be employed.

I claim:

1. The process of producing a tarry oil which comprises blending hot coal distillation gases enriched in condensable constituents by the distillation of tar therein, with hot coal distillation gases not so enriched and at a temperature substantially below the dewpoint of the enriched gases, thereby lowering the temperature of the combined gases below the dewpoint of oil constituents in the resulting mixed gases, and separately collecting the tarry oil which results from the condensation and separation of higher boiling constituents from the gases. 75

2. The process of producing tarry oil which comprises spraying coal tar into hot coke oven gases thereby distilling the tar and scrubbing entrained impurities from the gases with the tar, blending the resulting enriched and scrubbed gases with hot coke oven gases not so treated and at a temperature substantially below the dewpoint of the enriched gases, thereby producing a mixed gas of a temperature below the dewpoint of condensable constituents present in the mixed gases, and separately collecting the tarry oils which are separated by thus blending the gases. 85 90

3. The process of producing a tarry oil in the by-product recovery system of a coal distillation plant which comprises bringing coal tar into direct contact with a portion of the hot coal distillation gases thereby 100 distilling the tar and enriching the gases in condensable constituents, cooling another portion of the coal distillation gases to a regulated extent so that on mixing the gases the temperature of the combined gases will be below that of the dewpoint of higher boiling constituents present in the combined gases, combining the gases and separately collecting the tarry oil which separates on combining the gases. 110

4. The process of producing a tarry oil in the by-product recovery system of a coal distillation plant which comprises bringing coal tar into direct contact with a portion of the hot coal distillation gases thereby 115 distilling the tar and enriching the gases in condensable constituents, partially cooling the resulting enriched gases to separate higher boiling constituents therefrom, cooling another portion of the coal distillation gases to a regulated extent so that on mixing the gases the temperature of the combined gases will be below that of the dewpoint of higher boiling constituents present in the combined gases, combining the gases and separately collecting the tarry oil which separates from the combined gases. 120

5. The method of producing creosoting composition which comprises subjecting coal tar to regulated distillation in hot coke oven 125 130

gases, cooling other coke oven gases to a regulated extent, blending the enriched coke oven gases resulting from the distillation of the tar with the other gases in the proportion required to obtain a temperature such that the temperature of the resulting gases will be below that of the dewpoint of desired constituents present in the combined gases, and separately collecting the tarry oil thus produced, the distillation of the tar in the gases being so regulated that the free carbon content of the tarry oil produced is such as to make the tarry oil suitable for creosoting purposes.
